Attorney

UNITED STATES PATENT OFFICE.

GOTTLIEB STEINER, OF SOLOTHURN, SWITZERLAND, ASSIGNEE TO THE FIRM
SCINTILLA, OF SOLOTHURN, SWITZERLAND.

SHORT-CIRCUIT TERMINAL FOR THE MAGNETO-ELECTRIC IGNITION APPARATUS OF
INTERNAL-COMBUSTION ENGINES.

Application filed May 28, 1920. Serial No. 385,057.

To all whom it may concern:

Be it known that I, GOTTLIEB STEINER, a citizen of the Swiss Republic, and residing at Obach 304, Solothurn, Switzerland, have invented certain new and useful Improvements in Short-Circuit Terminals for the Magneto-Electric Ignition Apparatus of Internal-Combustion Engines, of which the following is a specification.

10 In connection with the magneto-electric apparatus of internal combustion engines it is customary, for the purpose of enabling the ignition of the engine to be prevented at will in case of necessity, to provide a contact piece by means of which the primary coil of the ignition apparatus can be short-circuited from the outside, for instance from the driver's seat, in the case of motor cars. From this contact piece, a cable is led into 20 the casing of the ignition apparatus where it is connected electrically to the non-earthed end of the primary coil.

The present invention has for its object to provide an improved construction of the 25 leading-in terminal (known in the trade as a "short-circuit terminal") for the said cable, by means of which the cable is connected to the primary ignition coil.

The improved terminal consists of a metal 30 body projecting into the interior of the casing of the ignition apparatus, and fixed in an insulated manner on the inside of the said casing, and of an insulating sleeve which is adapted to be screwed into the said metal 35 body from the outside by means of a screw-thread that is rigidly fixed to the said sleeve.

A terminal of this kind is illustrated by 40 way of a constructional example of the present invention in the accompanying drawings in which:

Figure 1 is a cross section;

Figure 2 is an elevation viewed from the inside of the casing, and

Figure 3 is a plan partly in section taken 45 through the attaching and jointing parts.

In the example, the metal body *a* is insulated from the bearing plate *m* of the ignition apparatus by means of the insulating washers and short tubes *b c d* and is attached by means of screws *e* from the inside 50 to the front wall of the bearing plate *m*.

k is the contact piece which bears against a central projection of the metal body *a* and

which is connected to one end of the primary coil of the fixed ignition winding. 55

The insulating sleeve *g* with the metal screw-thread *h*, is screwed from the outside of the bearing plate *m* into the contact body *a*; the short-circuit cable *p* being fixed in the central bore of the said sleeve. 60

A felt washer *f* closes the joint between the bearing plate *m*, the insulating plug *g* and the metal body *a* against the entry of dust and dirt. A pointed member *i* serves as an electrode for a safety sparking gap 65 which comes into action on the occurrence of an excess of potential or in the case of the sparking plug becoming defective.

Having now described my invention what I claim as new and desire to secure by Letters Patent is:—

1. A short circuiting device for the primary winding of the magneto electric ignition apparatus of internal combustion engines, including an internally screwed metal 75 socket fixed in an insulated manner inside the magneto casing, a cylindrical metal piece externally screwed for co-acting with said internally screwed socket and connecting one end of a short circulating cable to said internally screwed socket and a cylindrical extension, formed of insulating material, of said externally screwed metal piece external to said magneto casing and partly enclosing and rigidly attached to said externally 85 screwed metal piece, the said short circuiting cable traversing said externally screwed cylindrical metal piece and its insulated extension in an axial direction, thus permitting of the simultaneous attachment or removal of the cable and the said externally 90 screwed metal piece with its insulated extension.

2. A short circuiting device for the primary winding of the magneto electric ignition apparatus of internal combustion engines including an internally screwed metal 95 socket fixed in an insulated manner inside the magneto casing, a cylindrical metal piece externally screwed for co-acting with said internally screwed socket and connecting one end of a short circuiting cable to said internally screwed socket, a cylindrical extension formed of insulating material, of said externally screwed metal piece external to 100 said magneto casing and partly enclosing 105 said magneto casing and partly enclosing

and rigidly attached to said externally screwed metal piece, the said short circuiting cable traversing said externally screwed cylindrical metal piece and its insulated extension in an axial direction, thus permitting of the simultaneous attachment or removal of the cable and the said externally

screwed metal piece with its insulated extension, and a pointed projection on said metal socket adapted to serve as an electrode 50 for a safety sparking gap.

In testimony whereof I have signed my name to this specification.

G. STEINER.
